CLAIM

The ornamental design for the hair trimmer with vacuum system, as shown and described.

DESCRIPTION

FIG. 1 is a perspective view of the hair trimmer with vacuum system, showing our new design;

FIG. 2 is a front plan view thereof;

FIG. 3 is a side elevational view thereof, looking from the right side of FIG. 2;

FIG. 4 is a rear elevational view thereof; and

FIG. 5 is a side elevational view thereof, looking from the left side of FIG. 2;

FIG. 6 is a top plan view thereof; and,

FIG. 7 is a bottom plan view thereof.

The broken line environmental showing is for illustrative purposes only and forms no part of the claimed design.
